UNITED STATES PATENT OFFICE.

JOSEPH PEDERY, OF TRENTON, NEW JERSEY, ASSIGNOR OF ONE-FOURTH TO ALBERT E. SCHELLER, OF TRENTON, NEW JERSEY.

AUTOMATIC STOP MECHANISM.

1,107,343.

Specification of Letters Patent. Patented Aug. 18, 1914.

Application filed August 11, 1913. Serial No. 784,150.

To all whom it may concern:

Be it known that I, JOSEPH PEDERY, a citizen of the United States, residing at Trenton, in the county of Mercer and State of New Jersey, have invented certain new and useful Improvements in Automatic Stop Mechanisms, of which the following is a specification.

This invention has reference to automatic mechanisms arranged for use as a stopping means on wire drawing machines, and which is especially designed for throwing out the wire winding or take up devices in case that the wire becomes tangled on the coil or breaks when passing through the reducing die through which the wire is drawn.

My invention has for its object to provide a mechanism of the general character stated of a simple and economical construction, and in which the several parts are coöperatively so combined that the drawing machine is stopped or shut down automatically, in case the wire strand being drawn becomes tangled, or knotted, or broken.

Another object of my invention is to provide a simple and effective means for stopping or throwing out the wire take up or winding mechanism, and which is automatically set into operation through lever mechanism that is arranged for being set into action either by reason of the wire tangling or knotting before it reaches the reducing die or when the said wire breaks at such die.

With other objects in view that will hereinafter appear, my invention consists of the peculiar combination and novel arrangement of the parts hereinafter fully explained, specifically pointed out in the appended claims and illustrated in the accompanying drawings, in which:

Figure 1 is a perspective view of a wire drawing mechanism in which is embodied my invention, the parts being shown in a normal or running position. Fig. 2 is a side elevation partly in section of my improved wire drawing machine, the parts being shown in full lines at the normal or running position, and at the "stopping" position in dotted lines. Fig. 3 is a perspective view, parts being in section, of the reducing die and the shiftable lever devices that actuate the stopping lever controlled devices, and Fig. 4 is a similar view of the means for

lifting the wire take up cone roller out of 55 rotative connection with the driving shaft.

In the drawing, 1 designates a reducing die through which the wire strand, to be reduced, passes to the take up or winding means which in the present showing is a cone 60 pulley 8, vertically slideable on the driving shaft 80, provided with a clutch 81 for engaging the cone clutch face 82, of the pulley 8, it being understood that under normal conditions the cone pulley 8 rotates with the 65 driving shaft 80.

Die 1, before referred to, is slidably mounted on the table or frame, and it has a pendent arm 2 provided with an elongated slot 2^a, that receives the lateral stud 28 on 70 one end of a bell crank lever 28, the other end of which pivotally joins with the upper end of a plunger rod 22 that moves through and is guided in a slotted frame portion 23 and normally rests on the inner end of a lever 20, pivotally mounted on a stud 20^a, to swing in the vertical plane and with its outer end pivotally connected to the lower end of a lifting lever 19.

Lifting lever 19 carries a bifurcated head 30 block 19^a at the upper end, in which is journaled a grooved roller 12, which in my construction serves as a guide for the wire strand 29, the latter passing through the head block 19^a and under the roller 12, 85 which latter, as is clearly shown in the drawing, is in a plane below that of the reducing die 1, the reasons for which will presently appear, it being understood that the wire 29 that passes through the head block extends 90 from the wire reel.

By reason of coöperative arrangement of the parts so far described and as shown in the drawing, the operation thereof in case the wire strand 29 becomes tangled on the 95 coil, causes pressure on the guide wheel 12 and the wire in pulling out between the said wheel 12 and the die 1 lifts the lever 19 to the dotted position on Fig. 2, and in consequence swings the lever 20 down to the 100 dotted position, the said downward movement of which operates the lever mechanism that shifts the wire take pulley out of operative connection with the driving shaft, in the manner presently fully explained. 105

18 is a spring that is engaged by the lever 20, which is compressed when the lever is swung down as before mentioned and throws

the said lever up or back to normal when the drawing machine is again set into operative condition.

When the wire breaks at the die and the 5 normal pull strain on the die 1, in the direction of the arrow X, is thereby released, a spring 27 quickly slides the die 1 forwardly in the direction of the arrow y, and in doing so, rocks the bell crank lever 28, and since 10 the outer arm 28^a of the said lever 28 is swung down it shoves the plunger rod or lever 22, down, to cause it to swing the lever 20 down for operating the means that automatically releases the winding cone pulley 15 8 from the driving shaft, it being understood that the same operations of the parts, now to be described, take place under the downward thrust of the lever 20, no matter whether it is swung down by vertical pull of 20 the lifting lever 19 or the sliding motion of the die.

25 designates a plunger rod that slides in the frame 23, and it is normally projected to its upper position by a spring 23^a attached to a collar 24, clamped on the rod 25, and to a guide block 23^b, of the frame 23, as shown. Rod 25 is adapted to be engaged by and pushed down, by the lever 20 whenever it is moved down to its lowermost position, see 30 dotted lines Fig. 2, in either of the ways hereinbefore described. Rod 25 is joined to a bell crank lever 21, mounted on a support 16, and said crank lever is pivotally connected with a link bar 13 that pivotally joins with 35 guide arms 15, pivoted on a base support 30, whose upper or free ends engage the sides of a beam 3, pivotally mounted on a standard 32 that is pivotally supported at the lower end on the base support 30 to swing length- 40 wise of the machine, whereby to shift the beam 3 longitudinally, and at the same time, permit of its being vertically tilted, in the manner presently stated, to the dotted position shown. The pivoted standard 32 and 45 the beam 3 are held to their backward or normal positions, see full lines Fig. 2, by a coiled spring 34.

4 designates a constantly revolving crank on a driven shaft 40 and the said crank, 50 when the beam 3 is shifted forwardly by the link bar 13, engages the beam and tilts it to the dotted position shown.

5 designates a third plunger rod or lever, the lower end of which rides in a bearing 16^c, 55 in a support 16^b, and its lower end is held on the rear end of the beam 3, so that, as the beam 3 is tilted, the said rod 5 is pushed upward. The upper end of rod 5 is pivotally connected with a rocking lever 6, the 60 forward end of which rests on the free end 70 of a rocker frame 7, flexibly hung from the table or bed of the machine, and provided with angle arms 71, that carry friction rollers 72, which in turn engage the 65 under face of the flanged end of the cone

pulley 8, and which, when the lever 6 is swung down to tilt the frame 7, lifts the cone pulley 8 out of clutched engagement with the drive shaft. Rod 5 has a rack tooth 50 for engaging and interlocking with a bevelled latch tooth 18^a on a spring arm pendent from the table.

17 designates a hand lever connected to the spring latch lever for releasing it from the tooth 50, it being understood that when the mechanism described is actuated to automatically throw the drawing and winding devices out of operation. The operating lever devices which shift the lever 6 are held so that they do not perform their function at this time since the lever 5 is not held out of the position where it would be engaged by the beam 3, it being understood that said devices are restored to their normal or operative position by pushing the lever 17 in the direction of the arrow z to return the latch tooth 18^a to its locked engagement with the tooth 50.

As is best shown in Fig. 1, the lever 3 is provided with side flanges 90 which form stop members for engaging inwardly projected studs 91 on the guide arms 15 and which have for their purpose to limit the up-thrust of the lever 3.

From the foregoing taken in connection with the drawings, the complete construction, the manner in which my mechanism operates and its advantages will be readily apparent to those skilled in the art to which my invention relates.

What I claim is:—

1. In a stop mechanism for wire drawing machines, the combination with a driving shaft, a driven shaft, a wire takeup member loosely mounted on the said driven shaft, co-operating clutch connections on the shaft and takeup member and a drawing die, of means controlled by the breaking or tangling of the wire for shifting the clutch connections whereby to release the takeup member, the said means including a tripper device constantly movable with the driving shaft, said clutch shifting means including a tilttable lever, a rocker lever co-operatively connected with the said tilttable lever and having one end held adjacent to the path of movement of the tripper device, and means connected with the said clutch shifting means and with the wire strand being drawn, adapted for forcing the rocker lever into position to be engaged by the tripper on the driving shaft when the wire strand becomes tangled or broken.

2. In a stop mechanism, a continuously rotating driving shaft, a spindle geared to turn with the said shaft and a takeup bobbin mounted on said spindle, a clutch for operatively releasing said bobbin from said spindle, a rocker arm for raising said clutch, a crank driven by said shaft, a pivotally and

reciprocally mounted beam adapted to be projected into the path of said crank, means continuously tending to hold said beam out of the path of said crank, a connection between said clutch operating rocker arm and said beam for rocking said arm when said beam is projected into the path of movement of said crank and tilted thereby, and a mechanism for reciprocating said beam, a movable drawing die, and a connection including a system of levers between said die and said beam for projecting said beam into the path of said crank when the wire breaks between the die and the reel, and means opposing the tension of the wire for continuously tending to move said die in one direction.

3. In a stop mechanism, a continuously rotating driving shaft, a spindle geared to turn with said shaft and a takeup bobbin mounted on said spindle, a clutch for operatively releasing said bobbin from said spindle, a rocker arm for raising said clutch, a crank driven by said shaft, a pivotally and reciprocally mounted beam adapted to be projected into the path of said crank, means continuously tending to hold said beam out of the path of said crank, a connection between said clutch operating rocker arm and said beam for rocking said arm when said beam is projected into the path of movement of said crank and tilted thereby, and a mechanism for reciprocating said beam, a movable drawing die, and a connection including a system of levers between said die and said beam for projecting said beam into the path of said crank when the wire breaks between the die and the reel, means opposing the tension of the wire for continuously tending to move said die in one direction, and a latch device coöperative with said rocker arm for holding said clutch "out" and a finger engageable means for releasing said latch at the will of the operator.

45 4. In a stop mechanism, a continuously rotating driving shaft, a spindle geared to turn with said shaft and a takeup bobbin mounted on said spindle, a clutch for operatively releasing said bobbin from said spindle, a rocker arm for raising said clutch, a crank driven by said shaft, a pivotally and reciprocally mounted beam adapted to be projected into the path of said crank, means continuously tending to hold said beam out of the path of said crank, a connection between said clutch operating rocker arm and said beam for rocking said arm when said beam is projected into the path of movement of said crank and tilted thereby, a mechanism for reciprocating said beam, a movable drawing die, a connection including a system of levers between said die and said beam for projecting said beam into the path of said crank when the wire breaks between the die and the reel, means opposing the

tension of the wire for continuously tending to move said die in one direction, said beam projecting mechanism including a link bar operatively connected with said beam, a guide frame, a plunger operating in said guide frame, a power transmitting connection between said plunger and said link bar, a second plunger operating in said frame, and a resilient connection between said second plunger and said first plunger, and an operative connection between said second plunger and said drawing die whereby when said drawing die is released, said second plunger will be depressed and thereby operate said first mentioned plunger to project the beam into the path of said crank.

5. In a stop mechanism, a continuously rotating driving shaft, a spindle geared to turn with said shaft and a takeup bobbin mounted on said spindle, a clutch for operatively releasing said bobbin from said spindle, a rocker arm for raising said clutch, a crank driven by said shaft, a pivotally and reciprocally mounted beam adapted to be projected into the path of said crank, means continuously tending to hold said beam out of the path of said crank, a connection between said clutch operating rocker arm and said beam for rocking said arm when said beam is projected into the path of movement of the said crank and tilted thereby, and a mechanism for reciprocating said beam, a movable drawing die, and a connection including a system of levers between said die and said beam for projecting said beam into the path of said crank when the wire breaks between the die and the reel, means opposing the tension of the wire for continuously tending to move said die in one direction, a latch device coöperative with said rocker arm for holding said clutch "out", a finger engageable means for releasing said latch at the will of the operator, said beam projecting mechanism including a link bar operatively connected with said beam, a guide frame, a plunger operating in said guide frame, a power transmitting connection between said plunger and said link bar, a second plunger operating in said frame, and a resilient connection between said second plunger and said first plunger, an operative connection between said plunger and said drawing die whereby when said drawing die is released, said second plunger will be depressed and thereby operate said first mentioned plunger to project the beam into the path of said crank.

6. In a stop mechanism, a continuously rotating driving shaft, a spindle geared to turn with said shaft and a takeup bobbin mounted on said spindle, a clutch for operatively releasing said bobbin from said spindle, a rocker arm for raising said clutch, a crank driven by said shaft, a pivotally and

- reciprocally mounted beam adapted to be projected into the path of said crank, means continuously tending to hold said beam out of the path of said crank, a connection between said clutch operating rocker arm and said beam for rocking said arm when said beam is projected into the path of movement of said crank and tilted thereby, a mechanism for reciprocating said beam, a movable drawing die, a connection including a system of levers between said die and said beam for projecting said beam into the path of said crank when the wire breaks between the die and the reel, means opposing the tension of the wire for continuously tending to move the said die in one direction, said beam projecting mechanism including a link bar operatively connected with said beam, a guide frame, a plunger operating in said guide frame, a power transmitting connection between said plunger and said link bar, a second plunger operating in said frame, a resilient connection between said second plunger and said first plunger, an operative connection between said second plunger and said drawing die whereby when said drawing die is released, said second plunger will be depressed and thereby operate said first mentioned plunger to project the beam into the path of said crank, a lever projecting into said guide between said plungers and operated by the movement of said plungers, a tension roller and a lifting bar carrying said tension roller and connected with said last named lever whereby when said die is released by the breaking of the wire, said tension roller will also be released.
7. In a stop mechanism, a continuously rotating driving shaft, a spindle geared to turn with said shaft and a takeup bobbin mounted on said spindle, a clutch for operatively releasing said bobbin from said spindle, a rocker arm for raising said clutch, a crank driven by said shaft, a pivotally and reciprocally mounted beam adapted to be
- projected into the path of said crank, means continuously tending to hold said beam out of the path of said crank, a connection between said clutch operating rocker arm and said beam for rocking said arm when said beam is projected into the path of movement of the said crank and tilted thereby, and a mechanism for reciprocating said beam, a movable drawing die, a connection including a system of levers between said die and said beam for projecting said beam into the path of said crank when the wire breaks between the die and the reel, means opposing the tension of the wire for continuously tending to move said die in one direction, a latch device co-operative with said rocker arm for holding said clutch "out", a finger engageable means for releasing said latch at the will of the operator, said beam projecting mechanism including a link bar operatively connected with said beam, a guide frame, a plunger operating in said guide frame, a power transmitting connection between said plunger and said link bar, a second plunger operating in said frame, a resilient connection between said second plunger and said first plunger, an operative connection between said second plunger and said drawing die whereby when said drawing die is released, said second plunger will be depressed and thereby operate said first mentioned plunger to project the beam into the path of said crank, a lever projecting into said guide between said plungers and operated by the movement of said plungers, a tension roller and a lifting bar carrying said tension roller and connected with said last named lever whereby when said die is released by the breaking of the wire, said tension roller will also be released.

JOSEPH PEDERY.
